VALVE

Filed April 5, 1928

UNITED STATES PATENT OFFICE

PETER PAYNE DEAN, OF NEW CANAAN, CONNECTICUT, ASSIGNOR TO THE LIMITORQUE CORPORATION, A CORPORATION OF NEW YORK

VALVE

Application filed April 5, 1928. Serial No. 267,669.

The invention relates to valves for controlling the flow of fluids, particularly to valves of the type embodying a swinging or pivoted disk member, and adaptable more especially to high temperature and high pressure conditions. The invention is concerned specifically with an improvement in means for effecting the balance or equalization of the fluid pressures existing on opposite sides of the disk member of such valves to allow for readily manipulating the same, as in opening the valve under load conditions.

As is well understood in the art, it is common practice in connection with both steam and water lines to provide some form of bypass around the disk of a valve located therein in order to convey fluid from the pressure or live side of the valve port to the empty or dead side, for example as in the case of steam, to warm up the line beyond the valve and create a pressure therein substantially equal to that prevailing in the live side of the valve. By this expedient, the valve disk may be moved without undue effort; and it is the object of the present invention to provide in a valve novel means for effecting this by-passing of fluid from one side of its disk to the other which means, moreover, are to be carried by the disk itself and operable by the mechanism generally employed to move the valve disk off its seat. A further object of the invention resides in an arrangement whereby an abrasive material may readily be introduced or injected into the valve for grinding into its seat an auxiliary valve piece, employed for the by-passing operation aforesaid, and without requiring removal of the said valve disk or of parts other than the main cover of the valve.

The nature of the invention, however, will best be understood when described in connection with the accompanying drawings, in which:

Fig. 1 is a longitudinal section through a swing-disk type of valve embodying the novel by-passing means.

Fig. 2 is a detail sectional view of the valve disk and associated parts, with the by-pass indicated in the fully opened position; and

with the means for admitting abrasive material in position.

Fig. 3 is a transverse section taken on the line 3-3, Fig. 2 of the drawings.

Referring to the drawings, 10 designates a casing or body of a valve, designed of a more or less spherical form, and provided with the inlet 11 and the outlet 12. An elliptical opening or hand hole is arranged, also, in the top of said body and is adapted to be closed by a suitable removable cover member 13 so that access may conveniently be had to its interior.

Outlet 12, moreover, is provided with a seating ring 14 which is to be securely fastened thereto, as by welding; and there is adapted to contact with said ring a movable valve element shown as the closure disk 15 which is mounted, as hereinafter more fully set forth, upon the inner end of a swingable arm 16. The latter is secured to an operating or rock shaft 17 which extends into the valve body to support said arm and whereby the said valve disk may be swung into the closed position, indicated in Fig. 1, or into the open position, indicated in Fig. 2, by correspondingly rocking said shaft as is well understood in the art.

The invention relates more particularly to the provision of means for by-passing fluid from the inlet 11 to the outlet 12 through an opening 30 in the said valve disk 15 itself. In accordance therewith, the said disk is provided with a central enlargement or boss 15' bored axially through, the bore at the inner end being provided with a shouldered portion 18 to which is attached in manner to prevent leakage a metal seat ring 19.

The free end of arm 16, moreover, is turned inwardly to extend into said bore of the enlarged portion, and provides a spindle 20 coaxial therewith. Over the free or outer end of this spindle is screwed a ball or semi-spherical member constituting an auxiliary valve piece 21 which is adapted to seat against the ring seat 19 to effect a substantial seal thereat.

The said valve piece 21, furthermore, is provided circumferentially with a plurality of peripheral and longitudinally extending

grooves 22 which, however, do not extend over the normal sealing portion of said valve piece. Immediately behind said valve piece and fitted over the stem 20 is a compression spring 23 which is held in position by means of an annular nut 24 located about the said stem and secured into the bore of the enlarged portion 15' by screwing the same therein, as indicated. By this expedient, a substantial pressure may be exerted between the valve disk, as an abutment, and the valve piece 21 axially movable with respect to spindle 20 and mounted at the outer end thereof. This effects a seal thereby at the seat ring 19, the sealing action being assisted also by the fluid pressure prevailing on the inlet side of the valve disk 15.

When the valve is closed, that is when its disk 15 is seated against the seat ring 14, as indicated in Fig. 1 of the drawings, the auxiliary valve piece 21 aforesaid would also be maintained in sealed position as hereinbefore described; and under normal operating conditions, an extremely heavy pressure per square inch on the said disk 15 would prevail so that it would, under usual conditions, be practically impossible to move said disk away from its seat without the application of undue effort.

With the novel construction, however, should it be desired to open the valve, that is to say move the valve disk 15 away from contact with its seat 14, as by accordingly rotating the shaft 17, it will be apparent that the first effect of the rocking of said arm 16 in a direction away from outlet 12 will be to compress the spring 23. This action, it will be appreciated, is effected against a much less force, due to the smaller area involved, than prevails upon the valve disk 15 as a whole.

The valve piece 21 is thereby drawn with arm 16 from its seat 19 and allows the fluid to leak through to the outlet side of the valve disk, said fluid passing first through the annular space between spindle 20 and nut 24, then through the spring chamber behind the valve piece, and finally through the peripheral grooves 22 and past the seat 19 through the inner end of the bore of said enlarged portion 15' of the valve disk.

The pressures thus become substantially balanced upon opposite sides of the valve disk 15 which may then be opened without requiring any appreciable effort after spring 23 has been fully compressed, while the full operating pressure applied to the disk 15 during the first stage prevents the said valve piece from moving away from its disk.

This particular arrangement in connection with the valve disk lends itself, also, to convenient grinding of the auxiliary valve piece 21 through the ready provision of means for injecting suitable abrasive material between said valve and its seat. Reference being had

more particularly to Fig. 2 of the drawings, it will be noted that when the valve disk is thrown fully open, the auxiliary valve is substantially coaxially positioned with respect to the hand hole in the top of the valve. If, therefore, the cover 13 be removed, access may readily be had to said valve disk; and the outer portion of the longitudinal bore therethrough is threaded as at 30, to the end that it may receive a tubular member 31, Fig. 2 of the drawings, similarly threaded at its one end and through which the desired abrasive material may be delivered between the valve and its seat. To effect for this purpose a separation between the disk 15 with seat 19 and the valve piece 21, a perforated bar 32 may be placed on the casing over the hand hole therein after removing cover 13, and through which bar the tubular member 31 is then caused to pass and its inner end threaded into the said disk. The outer end of the tubular member, furthermore, is threaded and adapted to receive a nut 33 which, when tightened up, will bear against said bar to draw up the disk 15 with seat 19 to separate the latter from the valve piece 21, arm 16 retaining its position for the fully opened valve disk 15 aforesaid. Thus, there is no necessity for removing the disk itself or parts other than the main cover of the valve in order to provide suitable abrasive material for grinding of the said auxiliary valve piece.

The novel arrangement herein set forth, it will be appreciated, requires no additional external apparatus for effecting the by-passing of fluid from the inlet to the outlet sides of the valve, the same being effected solely by the actuation of the usual valve rock shaft, as the shaft or valve stem 17, for controlling the swinging of the valve disk proper.

The said auxiliary mechanism, also, is carried by the disk of the valve; and, furthermore, there is required no external pipe connections with independent valves and operating mechanism therefor, such as are usually employed for by-passing purposes, nothing being visible, in the novel arrangement externally of the valve casing, to indicate that such valve is provided with by-passing means.

I claim:

1. A high-pressure valve, comprising a casing provided with an inlet and an outlet and the latter affording a valve seat, a swinging valve disk adapted to close the outlet at said seat and having a portion bored through from one side to the other, a rock shaft, an arm movable therewith having a spindle extending into the bore of said disk, a valve piece mounted on said spindle to seal the bore of the disk and movable with said arm relatively to said disk, an annular nut mounted loosely about the outer portion of the spindle and in threaded engagement with the disk, and resilient means located between said nut and the valve piece urging the latter to a seal.

ing position in its valve disk for separation therefrom only when the rock shaft is actuated.

2. A high-pressure valve, comprising a casing provided with an inlet and an outlet and the latter affording a valve seat, a swinging valve disk adapted to close the outlet at said seat and having a portion bored through from one side to the other, a rock shaft, an arm movable therewith having a spindle extending into the bore of said disk, a semi-spherical valve piece provided with peripheral grooves, mounted on said spindle to seal the bore of the disk and movable with said arm relatively to said disk, an annular nut mounted loosely about the outer portion of the spindle and in threaded engagement with the disk, and resilient means located between said nut and the valve piece urging the latter to a sealing position in its valve disk for separation therefrom only when the rock shaft is actuated.

3. A valve, comprising a casing provided with an inlet and an outlet and the latter affording a valve seat, a swinging valve disk adapted to close the outlet at said seat and having a portion bored through from one side to the other and counterbored at the outer end to afford a shoulder, a seat ring secured thereto at the shoulder, a semi-spherical valve piece secured to the outer end of the spindle and normally seating on the seat ring, said valve piece being provided with peripheral grooves, an annular nut about said spindle secured in the inner end of the bore, and a spring between the said valve piece and said annular nut to normally maintain the said valve piece seated.

4. A valve, comprising a casing provided with an inlet and an outlet and the latter affording a valve seat, a swinging valve disk adapted to close the outlet at said seat and having a portion bored through from one side to the other, a rock shaft, an arm movable therewith having a spindle extending into the bore of said disk, and a valve piece mounted on said spindle to seal the bore of the disk and movable with said arm relatively thereto, the outer end of the bore being threaded to receive a tubular member for delivering abrasive material to the valve piece.

5. A valve, comprising a casing having a hand hole and provided with an inlet and an outlet, the latter affording a valve seat, a swinging valve disk adapted to close the outlet of said seat and having a portion bored through from one side to the other and adapted to be positioned coaxially with said hand hole, a rock shaft, an arm movable therewith having a spindle extending into the bore of said disk, a valve piece mounted on said spindle to seal the bore of the disk and movable with said arm relatively to said disk, resilient means acting on said valve piece to effect normally the sealing of the same, a

tubular member adapted to be inserted through said hand hole and threaded into the bore of said disk when the latter is positioned coaxially with said hand hole, a bar fitting over the outer end of said tubular member and upon the valve casing, and a nut working over the outer end of said tubular member against said bar.

In testimony whereof I affix my signature.

PETER PAYNE DEAN.
